[57] CLAIM

The ornamental design for a housing for cleaning implement, as shown and described.

DESCRIPTION

FIG. 1 is a perspective view of a housing for cleaning implement, embodying my new design;

FIG. 2 is a front elevational view thereof;

FIG. 3 is a side elevational view thereof, the opposite side elevational view thereof being a mirror image;

FIG. 4 is a rear elevational view;

FIG. 5 is a top view thereof; and,

FIG. 6 is a bottom view thereof.

The broken lines shown in the figures are for illustrative purposes only, and form no part of the claimed invention.
